UNITED STATES PATENT OFFICE.

CHARLES L. BELLAMY, OF ARLINGTON, NEW JERSEY.

DESIGN FOR PADLOCKS.

Specification forming part of Design No. **11,256**, dated June 24, 1879; application filed May 27, 1879.
[Term of patent 7 years.]

To all whom it may concern:

Be it known that I, CHARLES L. BELLAMY, of Arlington, Hudson county, New Jersey, have originated a new and ornamental Design for a Padlock, of which the following, in connection with the adjoined drawing, is a full, clear, and exact description.

The annexed drawing presents an elevation of the face or ornamental side of my newly-designed padlock.

The body of the lock, as illustrated, is of nearly semi-annular form or **U** shape, the body thus having a hollow or open center, and being designed upon the general form of a horseshoe, which, however, is modified and refined, so as to present a more artistic, novel, and pleasing effect. Thus the face of the body is level, and is destitute of the usual calks, and on each side is formed with a groove, from which square studs project level with the general surface, while on the arched portion of the body is formed a depressed panel of curved form, harmonizing with the curve of the arch,

as illustrated. This panel has, preferably, rounded ends, and also, preferably, contains a motto, such as "Good Luck," as illustrated, which is formed of letters in relief, which rise from the base of the panel level with the surface of the body.

What I claim is—

1. The design for a padlock, consisting of a body of horseshoe-shape, having substantially the appearance herein illustrated.
2. The design for a padlock, consisting of a horseshoe-shaped body, with a panel on the arched portion, substantially as herein set forth.
3. The design for a padlock, consisting of a horseshoe-shaped body, with a studded groove on each branch and a panel on the arch, substantially as herein illustrated.

CHARLES L. BELLAMY.
